(57) **CLAIM**

The ornamental design for an electronic vaporizer assembly as shown and described.

DESCRIPTION

FIG. 1 is a perspective view of the electronic vaporizer assembly showing my new design in assembled state of use.

FIG. 2 is another perspective view thereof.

FIG. 3 is another perspective view thereof.

FIG. 4 is a front view thereof.

FIG. 5 is a rear view thereof.

FIG. 6 is a left side view thereof.

FIG. 7 is a right side view thereof.

FIG. 8 is a top view thereof.

FIG. 9 is a bottom view thereof.

FIG. 10 is a perspective view of the electronic vaporizer assembly where the cover being removed from the assembly in FIGS. 1-9 for clarity of disclosure.

FIG. 11 is another perspective view thereof.

FIG. 12 is another perspective view thereof.

FIG. 13 is a front view thereof.

FIG. 14 is a rear view thereof.

FIG. 15 is a left side view thereof.

FIG. 16 is a right side view thereof.

FIG. 17 is a top view thereof.

FIG. 18 is a bottom view thereof; and,

FIG. 19 is an enlarged bottom view thereof.

The broken lines in the drawings depict portions of the electronic vaporizer assembly that form no part of the claimed design.
